UNITED STATES PATENT OFFICE.

HOWARD PEARSON BOOTH, OF MONTREAL, QUEBEC, CANADA.

FLUID-VALVE.

1,400,411.

Specification of Letters Patent.

Patented Dec. 13, 1921.

Application filed March 29, 1919. Serial No. 286,137.

To all whom it may concern:

Be it known that I, HOWARD PEARSON BOOTH, a subject of the King of Great Britain, and residing at 881 Durocher 5 street, in the city and district of Montreal, in the Province of Quebec, the Dominion of Canada, have invented a new and useful Fluid-Valve, of which the following is the specification.

10 The invention relates to fluid valves as described in the present specification and illustrated in the accompanying drawings that form part of the same.

15 The invention consists essentially in the novel means employed for maintaining the valve on its seat, whereby the seating pressure of said valve remains constant.

20 The objects of the invention are to eliminate the leakages due to inefficient closures and thereby save the scoring and cutting of valve or seat by the escaping fluid; to effect economy in large works and other places by avoiding delays incident to the repairs necessary to the valves in the midst of important operations, which conditions are 25 particularly noticeable where large hydraulic presses are used; to devise a simple means for application to many forms of fluid valves wherever expansile fluid pressure 30 may be at hand; and generally to provide a cheap, efficient and durable construction for the aforesaid purposes.

35 In the drawings, Figure 1 is a sectional view, showing the invention as applied to a simple form of valve.

Fig. 2 is a plan view of the pressure casing, showing the interior in dotted lines.

Fig. 3 is a longitudinal sectional view of the pressure casing.

40 Fig. 4 is a detail of the piston packing washer.

Fig. 5 is a detail of the piston packing.

Fig. 6 is a detail of the piston.

Fig. 7 is a detail of the locking screw.

45 Fig. 8 is a view of hydraulic machine showing the application of this invention thereto.

Fig. 9 is a detail of the pneumatic valve closing device.

50 Like numerals of reference indicate corresponding parts in each figure.

Referring to the drawings, the valve 1 is

shown as engaging the seat 2 and from said valve the stem 3 projects outwardly through the gland 4.

55 The pressure casing 5 is formed with one or more expansion chambers 6, here shown as a pair of such chambers, and above said chambers 6 the inlet passage 7 leads to the inlets 8 at the upper end centrally of said 60 chambers, the outer end of said passage communicating with a source of compressed air or other expansile fluid under pressure.

65 The pistons 9 operate in the chambers 6 and are formed with a dished upper end 10 in which the flexible packing 11 is inserted and held therein by the washer 12 and screw 13.

70 The outer ends of the pistons 9 terminate in the teats 14, each of said teats engaging a valve stem for the purpose of maintaining the valve on its seat and entirely eliminating the use of springs for that purpose.

75 The air or other fluid is turned on to reach the passage 7 and from there enters 75 the inlets 8 to the chambers 6 and at once effects an outward movement of the pistons 9 and this holds the valves firmly to their respective seats and at the same time provides equal flexibility, for the valves may 80 be readily operated against the fluid pressure, as the latter will simply back up for the moment in its tank, receptacle or other source and immediately the valves are back on their seats the pressure will again move 85 the pistons outwardly against the valve stems.

90 Various changes may be made without departing from the spirit of the invention, so long as they remain within the scope of the claims for novelty following.

What I claim is:—

95 In fluid valves, a casing forming a terminal in a compressed air line of piping and communicating constantly with recesses in one wall forming plunger chambers, plungers operating in said chambers and having stems in continuous engagement with the stems of valves governing the operation of the hydraulic press.

100 Signed at the city of Montreal, Quebec, Canada, this 25th day of March, 1919.

HOWARD PEARSON BOOTH.
